SPARK PLUG WITH MULTIPLE CONDUCTIVE SEALS

Patrick N. Kesten, Davison, Mich., assignor to General Motors Corporation, Detroit, Mich., a corporation of Delaware

Filed Mar. 5, 1962, Ser. No. 177,423

4 Claims. (Cl. 313—145)

This invention relates to spark plugs and, more particularly, to a spark plug of the type having a silver center electrode and to a method for making same.

In recent years it has become the practice to use a solid silver center electrode in certain types of spark plugs, particularly those for use in two-cycle engines such as outboard marine engines, power lawn mower engines and the like. Such an electrode has the advantage of extremely high heat-conductivity and has been found to display exceptional wear characteristics. In the manufacture of such spark plugs, after the silver center electrode is inserted into the insulator it is necessary to hermetically seal the insulator against the egress of exhaust gases during spark plug operation. This is accomplished by inserting a conductive sealing material over the electrode and then applying pressure to the material such that it is pressed into sealing engagement with the insulator wall. In practice it has been found that quality control of such spark plugs is extremely difficult for the reasons that the relatively soft silver electrode tends to extrude out of the insulator while the pressure is applied. This unwanted extrusion causes the electrode firing tip to extend too far from the end of the insulator and it also frequently results in poor electrical contact between the top of the electrode and the conductive sealing material.

It is an object of the present invention to provide an improved silver electrode type spark plug which solves the aforementioned problem. Another object of the invention is the provision of an improved method for manufacturing such spark plugs which assures uniform quality control. Briefly, these objects are accomplished in accordance with the invention by inserting a charge of metal powder between the top of the silver electrode and the seal. The metal powder has been found to minimize extrusion of the silver electrode while pressure is applied in the sealing operation. Hence, excellent quality control is attained both as regards the electrode firing tip length and as regards the electrical contact between the electrode and the seal.

Other objects, features and advantages of the invention will appear more clearly from the following detailed description thereof made with reference to the accompanying drawing which shows a side view in section of a preferred embodiment.

Referring now to the drawing, the spark plug comprises a conventional, generally tubular steel shell 2 with ground electrode 3 welded to the bottom thereof and a ceramic insulator 4 secured concentrically within the shell in the conventional manner. The insulator has a centerbore with a straight cylindrical lower portion 5 of relatively small diameter and an upper cylindrical portion 6 of relatively large diameter, an internal annular shoulder 7 constituting the junction of these different sized bore portions. The conductive path through the insulator centerbore includes a solid silver center electrode 8 which is positioned in the small diametered centerbore portion 5 and a terminal wire 9 which extends into the large bore portion 6. A head 10 which is integral with the terminal wire 9 and abuts the top of the insulator serves as the electrical contact for the spark plug with the ignition system. The lower end portion of the wire 9 is embedded in a fused conductive glass seal 11 which can

2

consist of a mixture of about 45% borosilicate glass and 55% nickel or copper powder, such sealing mixtures being well known and described in prior patents such, for example, as United States Patent 2,248,415. In order to provide increased surface contact with the conductive glass seal the lower end of the wire 9 is preferably threaded as shown. The upper end of the silver electrode 8 is shaped with an enlargement in the form of a flange 12 which rests against the insulator shoulder 7. The portion of the electrode above the flange extends into the large centerbore portion 6 and is shaped with a plurality of circumferentially spaced, outwardly extending ribs 13 to increase its surface area. In accordance with the invention, a body of tightly compressed metal powder 14 extends between the conductive glass seal and the silver electrode and encircles the upper ribbed portion of the latter. In the embodiment shown, the powder 14 consists of nickel having a mixed grain size ranging from minus 325 mesh to minus 48 mesh. The use of mixed particles of the designated size range permits maximum filling around and between the ribs 13 in a close-packed relationship reducing voids which is believed to be a factor in minimizing extrusion. The powder also tends to distribute the sealing pressure and provides increased lateral support to the electrode due to the larger surface area of the ribs 13 as compared to the surface area of the electrode upper end. It will be understood, however, that other metal powders may be used within the purview of the invention.

In the manufacture of the spark plug, the silver electrode is inserted into the insulator centerbore from the top thereof until it rests in the position shown. Then a charge of nickel powder is poured into the centerbore against the top of the silver electrode. This is followed by the addition of a charge of glass-metal powder mixture after which the wire 10 is inserted. At this stage the bottom of the wire 9 will rest against the top of the glass seal charge and hence the head 10 will be spaced upwardly from the top of the insulator. Intense heat is then applied until the glass sealing material becomes molten, and downward pressure is applied to the wire 9 thereby compressing the metal powder 14 and causing the threaded end of the wire 9 to sink into the molten glass sealing material. Upon cooling at the conclusion of this operation the glass sealing material is bonded to the insulator and to the wire 9 thereby creating a hermetic seal.

As has been mentioned above, the big advantage to the metal powder layer is that it minimizes the tendency of the relatively soft silver electrode from extruding downwardly out of the centerbore and away from its flange 12 during the application of pressure in the glass sealing operation. Hence, there is assurance of proper spacing between the bottom of the center electrode and the ground electrode 3 upon final assembly of the plug, and there is also assurance of excellent electrical contact, through the metal powder, between the conductive glass seal and the top of the center electrode.

While in the preferred embodiment described, the seal comprises a fused conductive mixture of glass and metal powder, it will be understood that the invention also has utility in spark plugs wherein other types of pressed centerbore seals are used. For example, the centerbore seal can consist of a tightly pressed mixture of ceramic and metal powder or, as is sometimes used, a body of pressed fused glass with a thin metal wire extending therethrough to form the electrical connection between the terminal and the center electrode. These and other centerbore seals which require the application of pressure thereto during manufacture create the same problem as regards the use of a silver electrode, i.e., extrusion

of the electrode during manufacture. Hence, the present invention wherein metal powder is interposed between the center electrode and the seal will serve to advantage in all such spark plugs. It will be understood, therefore, that while the invention has been described specifically with reference to a preferred embodiment thereof, various modifications may be made, all within the full and intended scope of the claims which follow.

I claim:

1. A spark plug comprising an insulator having a centerbore therethrough, an elongated silver electrode in said centerbore having a firing tip portion at the lower end thereof and a ribbed portion at the upper end thereof, a pressed seal in said centerbore above said silver electrode and a mass of tightly packed metal powder in said centerbore below said seal surrounding said ribbed portion, said mass minimizing the tendency of said silver electrode to extrude during the manufacture of said plug. 15

2. A spark plug comprising an insulator having a centerbore therethrough, said centerbore having a lower portion of relatively small diameter, an upper portion of enlarged diameter and an annular shoulder at the junction of said portions, an elongated silver electrode in the lower portion of said centerbore having a firing tip portion at the lower end thereof and an enlargement at the upper end thereof positioned in said upper centerbore portion and abutting said annular shoulder, said silver electrode having a plurality of ribs above said enlarge- 20

ment a pressed seal in the upper portion of said centerbore and a mass of tightly packed metal powder in said centerbore below said seal surrounding said ribs, said mass minimizing the tendency of said silver electrode to 5 extrude during the manufacture of said plug of said silver electrode.

3. A spark plug as defined in claim 2 wherein the seal comprises a fused mixture of glass and metal powder.

4. A spark plug as defined in claim 2 wherein the packed metal powder is nickel having a mixed size range of from minus 325 to minus 48 mesh.
